(57) **CLAIM**

We claim the ornamental design for a surveillance camera pendant mount housing, as shown and described.

DESCRIPTION

FIG. 1 is a perspective view illustrating our new surveillance camera pendant mount housing design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a bottom plan thereof; and,

FIG. 7 is a top plan thereof.
